DESIGN FOR A CEREAL PITCHER

Marvin G. Yutzey, Moundsville, W. Va., assignor
to Fostoria Glass Company, Moundsville,
W. Va., a corporation of West Virginia

Application April 29, 1948, Serial No. 146,035

Term of patent 14 years

(Cl. D36—2)

To all whom it may concern:

Be it known that I, Marvin G. Yutzey, a citizen of the United States of America, residing at Moundsville, in the county of Marshall and State of West Virginia, have invented a new, original, and ornamental Design for Cereal Pitcher, of which the following is a specification, reference being had to the accompanying drawing, forming a part thereof, wherein:

Fig. 1 is a side elevational view of a cereal pitcher showing my new design;

Fig. 2, a front elevational view; and,

Fig. 3, a rear elevational view thereof.

I claim:

The ornamental design for a cereal pitcher, as shown.

MARVIN G. YUTZEY.
